M. JONICK

LIGHTING FIXTURE STRAP

Filed March 3, 1927

UNITED STATES PATENT OFFICE.

MICHAEL JONICK, OF NEW YORK, N. Y., ASSIGNOR TO JONICK-SIRKEN CO., INC., A CORPORATION OF NEW YORK.

DESIGN FOR A LIGHTING-FIXTURE STRAP.

Application filed March 3, 1927. Serial No. 20,953. Term of patent 3½ years.

To all whom it may concern:

Be it known that I, MICHAEL JONICK, a citizen of the United States, residing in New York, county of New York, and State of New York, and doing business at 13 Crosby Street, in said city, have invented a new, original, and ornamental Design for A Lighting-Fixture Strap, of which the following is a specification, reference being had to the accompanying drawing, forming part thereof, of which.—

I claim:

The ornamental design for a lighting fixture strap, substantially as shown.

MICHAEL JONICK. [L. s.]
